Filed Aug. 23, 1962, Ser. No. 218,917
8 Claims. (Cl. 230—69)

This invention relates to a cold cathode ionization vacuum pump and more particularly to a magnetron type ionization vacuum pump having a discharge region in which electric and magnetic fields are produced substantially at right angles.

The production of low pressures has been achieved in the past by the use of a combination of mechanical pumps and diffusion pumps. In recent years various types of ionization pumps have been developed. These pumps differ from the mechanical and diffusion pumps in that they do not remove gas from the vacuum system but rather by immobilizing the gas within the system by a combination of chemical adsorption and entrapping of the ions of gas. Ionization pumps contain no fluid and therefore have one salient advantage over diffusion pumps which use a fluid e.g. oil or mercury which can reach the vacuum system causing contamination.

There are two general types of ionization pumps known and in use at the present time. In the first type, which is known as a "sputter-ion" pump, the positive ions formed in the discharge region bombard a metal surface, usually titanium and sputter metal atoms from this surface. The sputtered material condenses on other portions of the device provided for this purpose, entrapping and absorbing the chemically active (other than inert) gases in the system. The second type of pump, which is known as a "getter-ion" pump contains a source of metal usually titanium, which is evaporated. This evaporated material condenses on surfaces provided in the system, entrapping and absorbing the chemically active gases.

The "sputter-ion" pump does suffer from a serious defect which might be called the "historical effect," and which is one aspect of the general re-emission effect. When a first gas A is fed into the system and pumped away, and then a second gas B is introduced, it has been found that gas B is pumped but a small amount of gas A is evolved from the pump. This effect can be nullified in "getter-ion" pumps by covering the pumped gas with a layer of evaporated metal to prevent the gas from being re-emitted.

All ionization pumps using a magnetic field in use at the present time are of the parallel-field type in that the electric and magnetic fields are parallel. Because of the geometry of parallel-field pump the magnets required to produce the magnetic field are large and heavy.

It is an object of the present invention to provide an ionization vacuum pump which is light in weight, simple in design, and has greatly increased pumping speeds in relation to its size and weight.

It is another object of the invention to provide an ionization pump that has its pumping area separated from the discharge region allowing wide flexibility in the design of the pumping region.

Another object of this invention is to provide an ionization pump in which the magnetic field structure forms part of or is in close proximity to the envelope thus achieving a lighter and more efficient device.

Another object of this invention is to provide a pump whose geometry is such that a tube of large diameter can be readily used to connect the pump to the system required to be evacuated, allowing high pumping speed.

These and other objects of the invention are realized by providing an ionization pump comprising a gas-tight enclosure defining two interconnected volumes, the first

2

said volume defining a discharge region and the second said volume defining a pumping region, means for connecting the pumping region to a system that is to be evacuated, a metallic structure mounted in the pumping region to provide metallic atoms for the absorbing of the gas molecules being pumped, a magnetic circuit forming part of said enclosure and having poles forming a magnet gap region therebetween, said magnet gap region being said discharge region, a permanent magnet in said magnetic circuit to produce a strong magnetic field in the discharge region, a cathode positioned adjacent the interconnection between the pumping region and the discharge region, an anode positioned adjacent the magnet gap and opposite the said cathode, and lead means to supply a potential to the anode to produce an electric field in the discharge region, said electric field being transverse to the said magnetic field.

In drawings which illustrate embodiments of the invention,

FIGURE 1 is a cross-sectional view of a "getter-ion" pump according to the invention,

FIGURE 2 shows section A—A of FIGURE 1,

FIGURE 3 is a three-quarter view of a "getter-ion" pump according to the invention showing the positioning of the permanent magnets,

FIGURE 4 is a plural version of the pump capable of increased pumping speeds.

Referring to the drawings, FIGURE 1 shows a getter-ion pump according to the invention having an envelope indicated generally as 1, formed by an upper pole piece 7 and a lower pole piece 8, a generally cylindrical shaped outer barrier wall 13 made of stainless steel or other non-magnetic material, a glass-to-metal seal 6 and tubular member 11 which would be connected to the system to be evacuated. This envelope defines a first volume shown generally as 2, to be referred to below as the pumping region. Pole pieces 7 and 8 have raised portions extending towards each other, forming north and south magnetic poles N and S and defining a second region (magnet gap) between them shown generally as 3. The poles should be relatively close to each other so that a strong magnetic field can be produced in the magnet gap. This requirement however must be consistent with the need to provide space for a discharge of sufficient size to be formed in the gap. The faces of the magnetic poles are covered with thin sheets 10 of a metal preferably titanium. Permanent magnets 14 which are magnetized along their length are positioned to contact pole pieces 7 and 8 which are preferably made of low reluctance mild steel to form a magnetic circuit and provide a strong magnetic field in magnet gap 3. Cylindrical tubes 9 of sheet titanium are positioned adjacent the interconnection between pumping region 2 and magnet gap 3 and form, with sheets 10, a cathode. An anode in the form of a cylindrical ring 12 is positioned outwardly of magnet gap 3. The cathode 9 and 10 and pole pieces 7 and 8 are operated at ground potential and anode 12 is operated at high positive potential with the result that an electric field is set up in the magnet gap region 3 generally at right-angles to the magnetic field mentioned above.

An evaporator 20 is mounted on rod 5 having a heater winding 21 through which current can be passed by means of lead 22 which passes through glass seal 6. An accelerator electrode 23 in the form of two cylindrical tubes is positioned inwardly of cathode tubes 9. Rods 24 passing through the glass seal 6 hold the accelerator electrodes in position and provide an electrical connection so that the accelerator electrodes can be operated at a negative potential with respect to the cathode. A typical evaporator would comprise a sapphire rod on which is wound a tungsten heater wire, the heater wire in turn having a winding of titanium metal wound over its

surface. Rod 15 also acts as an electrical lead for the node and would be connected at 17 to a source of high direct current voltage. Barrier wall 13 is sealed to upper pole pieces 7 by means of an insert ring 32 which is welded or brazed to barrier wall 13 and bolted to pole piece 7 by several bolts 31. A gold wire O ring seal 33 is compressed by the tightening of bolts 31 providing the required seal between pole piece 7 and insert ring 32. Barrier wall 13 is welded or brazed to lower pole piece 8. Cylindrical member 11 is connected by means of a glass-to-metal seal to the tubulation 19 of the external system. The glass-to-metal seals can be standard Kovar-glass seals or ceramic-metal seals.

FIGURE 2 is a cross-sectional view A—A through the pump shown in FIGURE 1 and shows a method of mounting the permanent magnets 14. Although twelve magnets are shown in this figure the number could be varied quite widely. If pole pieces 7 and 8 shown in FIGURE 1 were constructed of permanent magnet material a more efficient device would be realized with the result that smaller or fewer permanent magnets would be required. From this figure it will be seen that the device as shown in FIG. 1 is, with the exception of the magnets, a figure of rotation and that the discharge region (magnet gap region) is an annulus completely encircling the pumping region. The discharge region which acts as a source of positive ions is able to supply ions to converge on the sputter cathode from a 360° sector. It can be seen that this results in a very efficient device.

In operation a discharge is established in the region bounded by the pole faces, the anode and the cathode. This discharge region coincides generally with the magnet gap region 3 mentioned above. Stray electrons in the discharge region are attracted towards the anode which is at a high positive potential with reference to the cathode. During their flight they strike gas molecules and if the electrons have sufficient energy they will ionize the gas molecules and produce electrons and positive ions. These positive ions are attracted towards the cathode and a large proportion will have sufficient energy to pass through slit 16 in the cathode tubes into the pumping region. In the pumping region the positive ions emerging from the slit are accelerated by a negative potential on the accelerator electrodes 23. The evaporator 20 is operated at a positive potential so that no positive ions can reach it. The positive ions move radially inward, turn around, and finally strike the accelerator electrode. A heating current passed through windings 21 evaporates titanium from the surface of the evaporator. This evaporated titanium condenses onto the surface of the accelerator electrode entrapping positive ions and absorbing molecules of the gas present. This gives rise to pumping action. The pumping region and the discharge region overlap to some extent with the discharge extending some distance into the pumping region and pumping action taking place in the discharge region. It should be pointed out that the action described here as absorption also includes the phenomenon usually described as adsorption.

The crossed electric and magnetic fields produce a discharge region similar to that in a magnetron. Electrons on their way toward the anode travel in spiral orbits which increases greatly the probability of their striking and ionizing a gas molecule. This results in highly increased efficiency.

As mentioned above, the getter-ion type of pump has the advantage that titanium metal can be evaporated onto the accelerator electrodes, before pumping a new gas, in sufficient quantity to cover up any atoms of a gas pumped during a previous operation. This eliminates the "historical effect" mentioned above.

Typical operating levels of voltage and current in a getter-ion pump of the type described above would be, for example, +2 to +7 kv. on the anode, —2 kv. on the accelerator electrodes, the evaporator slightly positive

or at ground or floating, and 7 to 8 amperes through the heating windings. The magnetic flux density in the gap would be approximately 1000 gausses. These values, of course, can be varied quite widely.

FIGURE 3 is a three-quarter view of a version of the pump showing external features especially the method of positioning of magnets 14.

If very fast pumping speeds are required, a plural version of the pump could be built and FIGURE 4 shows an example of a sputter-ion pump that would have parallel pumping action at three positions.

In the above description a typical example of a method of producing these pumps has been shown. It should be realized that the invention claimed in this application is directed to the novel arrangements of the magnetic circuit, the pumping region, the discharge region and the different electrodes positioned therein. The method of manufacture of these pumps could vary considerably within the scope of the invention. For example, the upper and lower pole pieces and the permanent magnets could be made as a unitary structure out of magnetic material. The stainless steel barrier wall could be in the form of a thin sheet in contact with a portion of the inner surface of this unitary structure. The anode structure positioning rod could be taken through both the stainless steel sheet and the magnetic material by means of a glass-to-metal seal. In some cases, the barrier wall might be eliminated altogether. In ionization pumps, titanium has been the metal most generally used to absorb and entrap the gas molecules. Other suitable metals such as molybdenum, tantalum, tungsten, zirconium, iron, calcium, barium, etc., might be used. The present invention is not primarily concerned with the metal used.

What is claimed is:

1. An ion pump comprising a cathode and an anode spaced apart to define therebetween a glow-discharge zone in which gas ionization is accomplished, electrical connections to said cathode and anode which when connected to an external electrical potential source will cause an electrical field to be established between the anode and cathode, a magnetic circuit arranged to establish a magnetic field transverse to the said electrical field, the glow-discharge zone having a long dimension transverse to the magnetic field which is at least several times greater than that dimension of the zone which is parallel to the magnetic field, an envelope defining a sorption zone in which ions and molecules are sorbed, the cathode extending along said long dimension, the cathode serving to separate the glow-discharge and sorption zones, the cathode being positioned to permit ready escape of positive ions from the glow-discharge zone into the sorption zone, a source of sorption metal positioned within said sorption zone, means defining a substantial sorption area in the sorption zone on which sorption metal is deposited, the sorption area being outside of the glow-discharge zone, and being substantially greater than the area of cathode separating the glow-discharge zone from the sorption zone, and means to connect the said sorption zone to a structure to be evacuated.
2. An ion pump comprising an anode and perforated cathode connected to a source of electrical potential so as to establish an electrical field between them, a magnetic circuit arranged to establish a magnetic field crossing the said electrical field generally at right angles, said crossed electrical and magnetic fields defining an annular glow-discharge ionization zone whose inner boundary is defined by said perforated cathode, an envelope defining a sorption zone whose outer boundary is defined by the perforated cathode, a source of sorption metal vapors positioned within the sorption zone, a substantial sorption area within the sorption zone on which sorption metal vapors are condensed, the sorption area being outside of the glow-discharge zone, and means to connect said sorption zone to a structure to be evacuated.
3. An ion pump as in claim 1 in which the source of sorption metal is an evaporator formed of a body

of sorption metal and a heater winding to evaporate said sorption metal.

4. An ionization pump as in claim 2 in which said perforated cathode is defined by a plurality of cathode plates defining spaces therebetween.

5. An ionization pump as in claim 2 in which said perforated cathode is defined by a pair of cathode rings, said rings being coaxial and longitudinally spaced to define a gas conductance path between said ionization and sorption regions.

6. A cold cathode ionization pump comprising a gas tight enclosure defining two interconnected volumes, the first said volume being a discharge region and the second said volume being a pumping region, means for connecting the pumping region to a system that is to be evacuated, a metallic structure mounted in the pumping region to provide metallic atoms for the absorbing of the gas molecules being pumped, a magnetic circuit forming part of said enclosure and having poles forming a magnet gap region therebetween, said magnet gap region being said discharge region, a permanent magnet in said magnetic circuit to produce a magnetic field in the discharge region, a cathode having a surface capable of absorbing gas molecules positioned adjacent the interconnection between the pumping region and the discharge region, an anode positioned adjacent the magnet gap region and opposite the said cathode, and lead means to supply a potential to the anode to produce an electrical field in the discharge region, said electric field being transverse to the said magnetic field.

7. A cold cathode ionization pump of the ion-getter type comprising a gas tight enclosure defining two interconnected volumes, the first said volume being a discharge region and the second said volume being a pumping region, means for connecting the pumping region to a system that is to be evacuated, a metal evaporator formed of a source of metal and a heater winding to evaporate said source of metal mounted in the pumping region to provide metallic atoms for the absorbing of the gas molecules being pumped, a magnetic circuit forming part of said enclosure and having poles forming a magnet gap region therebetween, said magnet gap region being said discharge region, a permanent magnet in said magnetic circuit to produce a magnetic field in the discharge region, a cathode having a surface capable of absorbing gas molecules positioned adjacent the interconnection between the pumping region and the discharge region, an anode positioned adjacent the magnet gap region and opposite the said cathode, and lead means to supply a potential to the anode to produce an electric field in the discharge region, said electric field being transverse to the said magnetic field.

8. An ionization pump as in claim 1 in which a plurality of stacked glow-discharge zones are provided adjacent a common sorption zone.
